UNITED STATES PATENT OFFICE.

WILLIAM H. MCKISSICK, OF TULSA, OKLAHOMA.

SAFETY SHEAVE BLOCK.

Application filed April 1, 1927. Serial No. 180,163.

This invention relates to new and useful improvements in safety sheave blocks.

The object of the invention is to provide a sheave block having line gaps in its guards normally closed by a shiftable closure manner which latter is arranged to be shifted to open said gaps, whereby the cable lines may be inserted or removed.

A particular object of the invention is to provide a rotatable closure member having oppositely reduced wings normally closing the line gaps of the block and arranged to open said gaps upon a partial rotation of said member.

15 A construction designed to carry out the invention will be hereinafter described, together with other features of the invention.

The invention will be more readily understood from a reading of the following specification and by reference to the accompanying drawings in which an example of the invention is shown and wherein:

Fig. 1 is a perspective view of a sheave block constructed in accordance with my invention and having its line gaps closed,

25 Fig. 2 is a transverse vertical sectional view of said block,

Fig. 3 is a perspective view of the shiftable closure member,

30 Fig. 4 is a sectional detail showing the closure member shifted to its open position,

Fig. 5 is a perspective view of another form of block constructed in accordance with the invention,

35 Fig. 6 is a transverse vertical sectional view of said block,

Fig. 7 is a perspective view of the shiftable closure member of said block, and

40 Fig. 8 is a sectional detail showing the closure member shifted to its open position.

In the drawings the numeral 10 designates an upper becket supporting a becket bolt 11 in its lower ends. The bolt penetrates the upper ends of vertical side bars 12 between which the becket is pivoted. A bottom becket 13 has its ends journaled on a bolt 14 penetrating the lower ends of the side bars.

At their central portions the bars support 50 a transverse axle 15 passing concentrically

between side plates 16, suitably fastened to the inner sides of said bars and positioned vertically between the beackets. While the side plates are shown as circular, they may be given any suitable shape.

On the axle a pair of sheaves or pulleys 17 are journaled between and parallel to the plates. The sheaves are separated by a vertical division or partition plate 18 which may conform to the size and shape of the 60 side plates. The plate 18 has a central aperture 19 whereby it is journaled on the axle 15. A finger 20 extending from the edge of the plate has an eye 21 for receiving the bottom becket bolt 14, whereby the partition 65 plate is held against rotation.

On each side plate and on opposite sides of the bars 12 I provide inwardly directed guard flanges 22 and 23, respectively. These guard flanges are at substantially right 70 angles to the side plates and extend transversely of the sheaves across the grooves or faces thereof. Each flange 22 has its inner edge inclined upwardly so as to overhang the contiguous downwardly inclined edge 75 of a closure wing 24 mounted on the edge of the partition 18; while each flange 23 has its inner edge inclined downwardly so as to underlie the contiguous overhanging edge 80 of a closure wing 25 mounted on the opposite edge of the partition.

The wings and flanges are preferably flush and are curved to conform to the side plates and the partition. The partition 18 with its wings constitutes a shiftable closure member. These flanges and wings being located on opposite sides of the side bars extend vertically and terminate short of the bottoms and tops of the side plates. The side plates and flanges form a cylindrical enclosure.

85 By removing the bolt 14 the partition is free to be rotated in a counter-clockwise direction, whereby the wings 24 and 25 are carried from between the flanges to the position shown in Fig. 4. This leaves gaps 90 between the flanges 22 and 23 through which the cable lines (not shown) may be inserted or removed.

95 When the gaps are closed and the parts are in their normal position, the flanges and 100

wings form guards protecting the workmen and preventing their fingers being caught between the lines and the sheaves. Above the sheaves arched guards 26 are fastened to the inner sides of the plates 16 so as to overhang the sheaves. These guards come close to the partition 18 and have cable notches 27 in their ends. It is necessary to mount the guards low enough to permit the wind 25 to swing thereover, as is shown in Fig. 4.

In Figs. 5 to 8 inclusive, I have shown another form designed for one sheave and similar in all respects, except as to size and number of parts. This form comprises an upper becket 30 mounted on a bolt 31 suspending side bars 32 carrying a bottom bolt 33 on which a bottom becket 34 is journaled. An axle 35 is carried by the bars and a sheave 36 is journaled on the axle between side plates 37.

One of the side plates has a flange 38 with its inner edge inclined downwardly on one side; while on its opposite side is a flange 39 with its inner edge inclined upwardly. The other side plate is free from flanges, but a shiftable member comprising a circular plate 40, wings 41 and 42 and a finger 43 is journaled on the axle 35, between said side plate and the sheave. The wings 41 and 42 are inclined to conform to the flanges and the side plate opposite the plate 40 has a guard 44 secured thereto.

Various changes in the size and shape of the different parts, as well as modifications and alterations, may be made within the scope of the appended claims.

What I claim, is:

1. In a safety sheave block, a support, a sheave carried by the support, an enclosure around the support and carried by the support, the enclosure having upright line gaps opposite the groove of the sheave on each side of said sheave, and a rotatable closure member journaled in the enclosure and having wings normally closing said gaps.

2. In a safety sheave block, a support, a sheave carried by the support, an enclosure around the support and carried by the support, the enclosure having upright line gaps opposite the groove of the sheave on each side of said sheave, a rotatable closure member journaled in the enclosure and having wings normally closing said gaps, and means for fastening said closure member against rotation.

3. In a safety sheave block, a support, a sheave carried by the support, an enclosure around the support and carried by the support, the enclosure having upright line gaps opposite the groove of the sheave on each side of said sheave, a rotatable closure member journaled in the enclosure and having wings normally closing said gaps, and a guard carried by the support overhanging the sheave and located so that one of the

wings may pass thereover when the closure member is rotated.

4. In a safety sheave block, a support, a sheave carried by the support, a cylindrical enclosure surrounding the sheave and carried by the support, said enclosure having opposite line gaps one of which flares upwardly and the other of which flares downwardly, and a rotatable closure member journaled in the enclosure and having oppositely flared wings conforming to the gaps and normally closing the same.

5. In a safety sheave block, a support, a sheave carried by the support, a cylindrical enclosure surrounding the sheave and carried by the support, said enclosure having opposite line gaps one of which flares upwardly and the other of which flares downwardly, a rotatable closure member journaled in the enclosure and having oppositely flared wings conforming to the gaps and normally closing the same, and an extension on the closure member for holding it against rotation and for rotating it.

6. In a safety sheave block, a pair of side bars, beackets at the top and bottom of said bars, an axle carried by said bars, a sheave journaled on the axle between the bars, side plates carried by the bars on each side of the sheave, guard flanges extending inwardly from the plates transversely of the sheave, the flanges of one plate being spaced from the flanges of the other plate to form gaps there-between, and a plate journaled on the axle and having wings fitting between the flanges in said gaps.

7. In a safety sheave block, a pair of side bars, beackets at the top and bottom of said bars, an axle carried by said bars, a sheave journaled on the axle between the bars, side plates carried by the bars on each side of the sheave, guard flanges extending inwardly from the plates transversely of the sheave, the flanges of one plate being spaced from the flanges of the other plate to form gaps there-between, a plate journaled on the axle and having wings fitting between the flanges in said gaps, a bolt on which the bottom becket is mounted, and a finger extending from the wing plate and engaging the bottom becket bolt.

8. In a safety sheave block, a pair of side bars, beackets at the top and bottom of said bars, an axle carried by said bars, sheaves journaled on the axle between the bars, side plates carried by the bars on each side of the sheaves, guard flanges extending inwardly from the plates transversely of the sheaves, the flanges of one plate being spaced from the flanges of the other plate to form gaps there-between, and a plate journaled on the axle between the sheaves and having wings fitting between the flanges in said gaps.

9. In a safety sheave block, a support, an enclosure carried by the support and having

line gaps on each side of said support, a sheave in the enclosure disposed diametrically between said line gaps, closure members normally closing said line gaps, and a common means for shifting said closure members, whereby both line gaps are opened at the same time.

10. In a safety sheave block, a support, an enclosure carried by the support and having

elongated line gaps on each side of said support, a sheave in the enclosure disposed diametrically between said line gaps, elongated closure members normally closing said line gaps and mounted on a common pivot, and a common means for rotating said closure members in unison to open said line gaps.

In testimony whereof I affix my signature.
WILLIAM H. McKISSICK.
